UNITED STATES PATENT OFFICE.

VICTOR E. EDWARDS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

METHOD OF AND APPARATUS FOR ROLLING ROUNDS.

1,193,001.

Specification of Letters Patent.

Patented Aug. 1, 1916.

Application filed November 23, 1914. Serial No. 873,463.

To all whom it may concern:

Be it known that I, VICTOR E. EDWARDS, a citizen of the United States, residing at Worcester, in the county of Worcester and 5 Commonwealth of Massachusetts, have invented a new and useful Improvement in Methods of and Apparatus for Rolling Rounds, of which the following, taken in connection with the accompanying drawings, is a specification.

The present invention relates to the production in a rolling mill of bars of circular cross section known as "rounds", and the said invention resides in a new and improved method of and apparatus for finishing "rounds", whereby the accuracy in section of "hand rounds" is obtained, together with the high output and correspondingly low cost of "guide rounds".

My present invention aims to combine all the advantages of the two known methods, above enumerated, in the production of accurate "rounds" at a high rate of output. The following description, taken in connection with the accompanying drawings, will serve to illustrate the principles underlying the production of "rounds" according to the method, and by the apparatus of my invention, the features of novelty being set forth 30 in the annexed claims.

In the said drawings, Figure 1 is a diagrammatic representation of so much of an arrangement of rolling mill apparatus as will serve to illustrate the principles of my invention. Fig. 2 is a diagrammatic representation of the several cross sectional shapes imparted to the rod or bar, in the production of a "round" by the present invention. Fig. 3 is a diagrammatic representation illustrating the method of producing "hand rounds", and Fig. 4 is a diagrammatic representation illustrating the method of producing "guide rounds".

Similar reference characters refer to similar parts throughout the different figures.

In the process of producing so-called "hand rounds" the billet is reduced to an approximate "round", slightly larger than the finished size, and is then introduced two 50 or more times, by hand, to the same finishing pass formed in a pair of rolls. Such a finishing pass is indicated in Fig. 3. It is well known that a bar even slightly out of round has a pronounced tendency to turn

down, when subjected to a rolling operation, 55 so that its major axis shall be horizontal. In finishing a bar by means of the pass shown in Fig. 3, of course the major axis must be kept vertical. In producing a "round" by this method, the operator firmly 60 grasps the rear end of the bar with a pair of tongs, and pushing the other end into the grooved rolls, follows the bar as it is rolled, carefully watching it and instantly opposing any tendency of the bar to turn 65 down either to the right or to the left. He does not release his grip on the bar until his tongs are closed to the rolls. The speed of the rolls is very slow, being limited to the speed at which a man can walk, and obviously only very short pieces can be prevented from turning down. Preceding subsequent introductions, the bar is given a quarter turn about its axis in order that the slight fins which have formed thereon by the 70 squeezing out of the metal, between the parting of the rolls and into the "tailored" cavities 1, may be eliminated. This method of finishing "rounds", while conducive to the production of "rounds" of excellent accuracy, is subject to extremely serious, in fact almost prohibitive, limitations, by reason of its very low output and consequently high producing costs, owing to the very low 75 speed at which the rolls must be run, and owing to the necessity for employing very short bars to avoid "turning down" in spite of the efforts of the operator.

In the well-known process of producing so-called "guide rounds", the bar goes but 90 once through the finishing pass. It is presented to the finishing pass in the form of an approximate ellipse, the major axis of which, in high tonnage mills, is usually made not less than fifty per cent. more than its 95 minor axis. This distinct ellipse has, of course, a strong tendency to "turn down", which tendency is resisted by side guides 2 placed close to the rolls. Such a finishing pass 3 and such side guides 2 are indicated 100 in Fig. 4. The ellipse must be decidedly flat in order to give the guides sufficient leverage to enable them to hold the ellipse from "turning down" or from jamming in the guides. When using flat ellipses with suitable side guides, there is no known limit to the length of the bars which may be 105 finished or to the speed at which the rolls

may be run. This combination of long lengths and high speed permits large outputs at low producing costs. These low producing costs explain why probably over 5 ninety-five per cent. of the "rounds" under two inches in diameter are finished on "guide mills". But it has not heretofore been possible to maintain accurate sections on "guide rounds".

10 Referring again to Fig. 4, I have said that the ellipse must be decidedly flat in order that the guides 2 may hold it from turning down. In common practice in high tonnage mills, the major axis of the ellipse is 15 seldom less than fifty per cent. greater than the minor axis, and the minor axis is seldom greater than twenty to twenty-five per cent. less than the diameter of the desired "round." In other words, the transition from the ellipse to the "round" involves a "side spread" 20 approximating twenty to twenty-five per cent. of the required diameter, as shown at 4, 4 in Fig. 4, over which there is almost no control, and yet it is required of the mill to 25 maintain the desired diameter within one per cent. It is, of course, obvious that a very slight change in size, shape or temperature of the elliptical section in any bar, or in any part of the length of any bar, will 30 produce a serious difference in the amount of "side spread," and the diameter of the bar measured horizontally will be objectionably more or less than it should be.

The makers of "rounds" are constantly 35 striving to maintain generous tolerances between maximum and minimum diameters, which will permit them to make large outputs with small percentage of rejections and, consequently, at low producing costs. On 40 the other hand, the users of these "rounds" are as constantly insisting on greater accuracy of section as affecting their cost of fabrication.

The present invention provides for the 45 virtual elimination of the above described errors arising in the production of "guide rounds," without sacrificing the high output and low producing costs of such a mill, and the apparatus by which this result is attained is shown in Fig. 1.

In Fig. 1 is shown, at the left hand side, 50 a series of roll housings 5, 6 and 7, the same representing diagrammatically the finishing end of a mill adapted for the production of 55 "guide rounds" according to the method hereinbefore described. The path of the material is indicated by the broken line 8, and the cross sectional shape and the orientation of the same both prior to and after its passage 60 through the successive passes of the rolls is indicated by the several cross sectional representations on opposite sides of the passes of the rolls. As shown, the final product of this mill is an approximate 65 "round," and the said "round," in the carry-

ing out of this invention, is purposely given a cross sectional area slightly in excess of the cross sectional area of the "round" which it is desired eventually to produce.

Referring to Fig. 2, the outer circle 9 indicates the average section of the approximate "round" produced by the guide mill at the left hand side of Fig. 1, and the slightly smaller circle 10 indicates the section of "round" which it is desired to produce by 70 the present process. The invention contemplates the continuous reduction of the "round" 9, to form the "round" 10, with the least opportunity for error to arise by reason of the successive changes in the shape of 75 the material during said reduction. To do this it is proposed to change the approximate "round" 9 into an approximate ellipse, as indicated at 11, Fig. 2, the minor axis of 80 said approximate ellipse being but slightly less than the desired diameter of the finished "round," and then instantly to change this 85 elliptical section to the finished "round." It will be seen that by reason of the relative roundness of the ellipse 11, the relatively 90 slight reductions required, and the correspondingly relative slight "side spread," indicated at 12, Fig. 2, which must be effected, the possible error in the cross sectional shape 95 and area of the finished round, due to uncertain "side spread," is reduced to a minimum.

In order to carry out the steps of my method above set forth, provision is made 100 for the formation of a free loop 13 in the bar 9 after the same is led to the pass in a pair of vertical rolls 14, Fig. 1, which impart thereto an elliptical section having the characteristic above set forth, namely, a minor axis only slightly shorter than its 105 major axis. An ellipse 11 of such proportions is incapable of being held from axial turning by the use of guides, by reason of its close approach to a circle, hence it is necessary to dispose the horizontal rolls 15, 110 which have a circular pass of the desired cross sectional area of the finished "round," in immediate juxtaposition to said vertical rolls 14. Therefore the ellipse 11, emerging 115 continuously from the pass between the rolls 14, is immediately subjected to a change in form and area by passage between the rolls 15, there being no opportunity for the elliptical bar to turn in the very limited distance 120 between the passes of the two sets of rolls. It will be clear from Fig. 2 that the amount of "side spread," indicated at 12, Fig. 2, is 125 very slight; furthermore, that the actual reduction in cross sectional area, in rolling from the ellipse 11 to the "round" 10 is much less than in the previously described method of producing "guide rounds." The product emerging continuously from the final pass between the rolls 15 is, therefore, necessarily more accurate in dimension than the prod-

uct of a guide mill, since in the latter, the final transition from an ellipse to a "round" is accompanied, not only by a relatively high reduction in cross sectional area, but 5 also by a very considerable degree of "side spread."

It is to be understood that "slightly elliptical," and similar terms used hereinafter in 10 the appended claims, refer to a cross sectional shape of bar which is not sufficiently flat to permit of holding up by means of side guides.

By my invention it is feasible to use a finishing ellipse that shall have a "side 15 spread" from the finishing oval to the finished "round" less than one-fifth that now common in finishing "guide rounds," hence it is reasonable to expect finished "rounds" with much less variation in their width 20 than formerly. In other words, it will be seen that I have combined the accuracy of "hand rounds" with the high output and consequently low cost of "guide rounds."

I claim,

25 1. A method of rolling "rounds", including the producing of an approximate "round" of slightly larger section than the required "round", rolling said approximate "round" to an ellipse whose minor axis is 30 slightly less than the diameter of the required "round", and reducing said ellipse to the required "round".

2. A method of rolling "round", including the producing by a continuous rolling 35 operation of an approximate "round" of slightly greater section than the required "round", continuously rolling said approximate "round" to an ellipse whose minor axis is slightly less than the diameter of the required "round" and producing from said 40 ellipse by a continuous rolling operation a "round" of the required diameter.

3. A method of rolling "rounds" of an accurate section, including the continuous 45 feeding of an approximate "round" of a section slightly greater than the section required to a rolling mill pass adapted to change said approximate "round" to an ellipse whose minor axis is slightly less than 50 the required diameter, and passing said ellipse continuously between rolls adapted to change said ellipse to a "round" of the required diameter.

4. A method of rolling metal bars to accurate circular section, including the production by a continuous rolling operation of an approximate "round" of slightly greater section than the final section desired, continuously rolling said approximate "round" to form an approximate ellipse having a 60 minor axis slightly less than the required diameter, providing for a free overfeed loop of the metal between the above mentioned rolling operations, and continuously reducing said approximate ellipse to a "round" of 65 the required diameter.

5. A three stand continuous mill for rolling "rounds", comprising a first stand to produce an approximate "round" slightly larger than the desired section, a second 70 stand to reduce said approximate "round" to an approximate ellipse, and a third stand to reduce said approximate ellipse to the finished "round", the last two stands of rolls having their axes at right angles to each 75 other and being in such juxtaposition as to prevent the approximate ellipse from turning down while between said stands and the first and second stands being separated to permit a free overfeed loop between them. 80

6. Means for continuously finishing a "round" from a "guide round" of slightly larger section, comprising a two pass continuous mill, having the two pairs of reducing rolls at right angles to each other 85 and in such juxtaposition as to prevent the metal from turning axially while between said pairs of rolls.

7. In apparatus for finishing metal bars to accurate circular section, the combination 90 with a "guide mill" for producing an approximate "round" of slightly larger section than the required section, of a two-pass continuous sizing mill having its two pairs of rolls at right angles to each other and in 95 such juxtaposition as to prevent axial turning of the metal while between said pairs of rolls and a space for permitting a free overfeed loop between said "guide mill" and said sizing mill. 100

Dated this twenty first day of November 1914.

It is hereby certified that in Letters Patent No. 1,193,001, granted August 1, 1916, upon the application of Victor E. Edwards, of Worcester, Massachusetts, for an improvement in "Methods of and Apparatus for Rolling Rounds," errors appear in the printed specification requiring correction as follows: Page 1, line 68, for the word "closed" read *close*; page 3, line 33, claim 2, for the word "round" read *rounds*; and that the said Letters Patent should be read with these corrections therein that the same may conform to the record of the case in the Patent Office.

Signed and sealed this 29th day of August, A. D., 1916.
